CLAIM

The ornamental design for a building block container, as shown and described.

DESCRIPTION

FIG. 1 is a top front perspective view of a building block container showing my new design;

FIG. 2 is a top rear perspective view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a top plan view thereof; and,

FIG. 8 is a bottom plan view thereof.

The broken lines illustrate the bounds of the claim and form no part of the claimed design.
